[57] CLAIM

The ornamental design for an electrical plug, as shown and described.

DESCRIPTION

FIG. 1 is an exploded perspective view of an electrical plug showing my new design, the removable identification ring being separated from the plug;

FIG. 2 is a perspective view thereof with the ring engaged with the plug;

FIG. 3 is a top plan view thereof, the bottom being identical;

FIG. 4 is a front elevational view thereof, the rear being a mirror image;

FIG. 5 is a left end elevational view thereof; and

FIG. 6 is a right end elevational view thereof.

FIG. 1

FIG. 2

FIG. 3

FIG. 4

FIG. 5

FIG. 6
